(57) **CLAIM**

The ornamental design for a tread of a tire, as shown and
described.

DESCRIPTION

FIG. 1 is a perspective view of the tread of a tire of the
present invention, it being understood that the pattern is
repeated uniformly throughout the circumference of the
tread; and,

FIG. 2 is a front elevational view of the tire tread shown in
FIG. 1.

The broken lines showing the tire inner beads and sidewalls
in FIGS. 1 and 2 are for illustrative purposes only and form
no part of the claimed design.
